Primary Examiner—Stella Reid
 Attorney, Agent, or Firm—Clifton Ted Hunt

[57] CLAIM

The ornamental design for a combined therapy chair and table, as described and shown in the drawings.

DESCRIPTION

FIG. 1 is a front, side perspective view of a combined therapy chair and table, showing my new design, the broken line showing is for illustrative purposes only and forms no part of the claimed design;

FIG. 2 is a front elevation view thereof;

FIG. 3 is a side elevational view thereof;

FIG. 4 is a top plan view thereof;

FIG. 5 is a rear elevational view thereof; and,

FIG. 6 is a side elevational view thereof with the chair extended longitudinally from the table and the table elevated.
